MARTIN LANDENBERGER, OF PHILADELPHIA, PENNSYLVANIA.

Design No. 4,165, dated June 21, 1870.

DESIGN FOR THE SHAPE OF A HOOD.

The Schedule referred to in these Letters Patent and making part of the same.

To all whom it may concern:

Be it known that I, MARTIN LANDENBERGER, of Philadelphia, in the county of Philadelphia and State of Pennsylvania, have invented and produced a new and original "Design for Shape of Hood," of which the following is a specification.

The nature of my design is fully represented in the accompanying drawing, to which reference is made.

Claim.

I claim as my invention—

The design for shape of hood, as shown.

In testimony whereof I have signed my name to this specification in the presence of two subscribing witnesses.

Witnesses: MARTIN LANDENBERGER,
J. M. MASON,
C. L. EVERETT.
